UNITED STATES PATENT OFFICE.

WILLIAM S. MARTIN, OF ROCHESTER, NEW YORK.

HOT-AIR FURNACE.

Application filed January 17, 1927. Serial No. 161,495.

The present invention relates to hot air furnaces and more particularly to the type in which outlet pipes lead from the heating drum at the top of the furnace in various directions. An object of this invention is to provide a novel construction for insuring the passage of heat from all of the outlet pipes. Another object of the invention is to provide the top of the furnace with a plurality of adjustable partitions mounted in a novel manner and adapted to vary the amount of heat supplied by the furnace to the different outlet pipes. Another object of the invention is to provide a means operable from the exterior of the furnace in a simple and novel manner for the purpose of providing individual compartments of desirable sizes from which the pipes lead.

To these and other ends, the invention consists of certain parts and combinations of parts, all of which will be hereinafter described; the novel features being pointed out in the appended claims.

In the drawings:

Fig. 1 is a plan view of a furnace constructed in accordance with this invention.

Fig. 2 shows the upper portion of the furnace in fragmentary section.

Fig. 3 is a bottom view of the top section of the furnace;

Fig. 4 is an enlarged fragmentary section showing the manner in which the partitions are supported and adjusted.

Fig. 5 is a section on the line 5—5, Fig. 4, and

Fig. 6 is a section on the line 6—6, Fig. 4.

In the illustrated embodiment of the invention 1 indicates the furnace casing, in this instance surmounted by the top section having a flange 3 fitting in the casing 1 and having a side wall 2 which tapers upwardly to a top plate 4. Within the top section is an inverted cone shaped member 5 which has its edges seamed to the top plate 4 and the side wall 2. This top section provides part of the heating drum from which the outlet flues 6 lead.

In the hot air furnaces now in general use, some of the outlet pipes owing to draft or other conditions carry off a greater amount of heat from the heating drum than others, making the functioning of such other flues difficult. In this invention, adjustable partitions are provided in the heating drum which will divide the drum into

a plurality of chambers preferably corresponding in number to the number of flues leading from the drum, with each chamber common to one of the flues, and the adjustment of the partitions permitting an increase or decrease in the size of the chamber to meet the conditions required. It has been suggested prior to this invention to divide the heating drum into chambers by partitions which are adjustable but so far as I am aware it has not been possible to move these partitions in a complete circle. Furthermore it has not been possible to obtain the adjustment of the partitions from the exterior of the furnace without at the same time providing openings through which the heated air may escape or dust may enter the heating drum to be carried therefrom into the building by way of the outlet flues.

In this embodiment of the invention, there is provided a central tubular bearing member 7 which is supported at the center of and depends from the top section, being externally threaded at 8 adjacent one end for engagement by nuts 9 two of which clamp the tubular bearing member 7 to the top plate 4 while the other two clamp said bearing member to the cone shaped wall 5. Within the heating drum is preferably formed an inwardly extending annular flange 10 which is concentric with the bearing member 7.

Mounted to turn on the bearing member are a number of partitions 11, the number being sufficient to provide chambers between them corresponding in number to the number of flues or outlets 6. Each of these partitions 11 has along its top edge a flexible strip 12 and along its vertical edge a flexible strip 13, these flexible strips being made in this instance of asbestos and forming a tight joint between the partitions and the walls of the top section. Each partition is mounted to swing on the bearing member 7 and to this end each has a bearing ring 14 detachably bolted at 15 thereto, said ring surrounding the tubular bearing member 7 and lying in an annular groove 16 formed in the surface of said tubular bearing member. Each bearing ring 14 supports a partition at its inner edge while the inwardly projecting flange 10 supports the partition at its outer edge. It is apparent that each partition may be swung in a complete circle and if de-

sired the number of chambers may be reduced by bringing two or more of the partitions in abutment, thus making it possible to feed all of the flues from one chamber or 5 any desired number of flues from one chamber, in addition to making it possible to obtain a chamber of any desired size for any one flue.

In order to effect the swinging of the partitions from the exterior of the furnace, each partition may be provided with its own operating means, the means in this instance comprises a rod 17 having a laterally turned screw threaded end 18 engaged by a sleeve 19 with internal right and left threads engaging also a screw threaded portion 20 on a rod 21 which is employed for reinforcing the lower edge of a partition 11. The rod 17 extends upwardly through the hollow 15 bearing member 7 and has an arm 22 extending outwardly therefrom in the plane of the partition 11 to which the arm is secured, this arm operating over the top plate 4. The opening in the tubular bearing member 7 is 20 of sufficient size to hold all of the rods 17.

With the end in view of preventing dust from passing into the furnace or hot air passing from the furnace by way of the tubular member 7, a novel closing means is 25 employed for closing the upper end of this tubular member. This closing means in this instance embodies a cup shaped member 23 secured to the top plate 4 between two of the nuts 9 and adapted to contain sand or 30 other sealing medium. An inverted cup shaped member 24 of smaller diameter than the cup shaped member 23 is received within the latter with its edges depending into the sand 25, thus sealing the end of the 35 tubular bearing member 7. So that the rod or operating members 22 will not interfere with the sealing of the cup shaped member 40 in the sand 25, each rod has a deflected portion 26 which is bent downwardly below 45 the edge of the cup shaped member 24 and then upwardly and outwardly over the edge of the cup shaped member 23. The sand does not prevent the movement of the rods 23 to adjust the partitions 11, but if the adjustment of the partition materially disturbs 50 the sand or the closure 24 then the rearrangement of the sand and the proper positioning of the closure 24 may be readily effected.

55 It is apparent, with this invention, it is possible to adjust from the outside of the furnace the sizes of the chambers formed between the partitions to meet the desired requirements as each partition has an operating portion extending to the exterior of the furnace. This operating portion connects with a partition in such a manner that the entrance of dust to the heating drum or the escape of heated air from the heating drum 60 is prevented. All of the operating members

connect with the partitions through a tubular bearing member at the center of the furnace. The tubular bearing member permits each partition to be swung in a complete circle so that in any position of adjustment, a partition can act as a wall of a chamber. A novel means is employed for supporting the partitions at their outer edges so that the sagging of the outer edge is prevented. 70

What I claim as my invention and desire to secure by Letters Patent is:

1. In a furnace, an inwardly projecting flange near the top of the furnace, a bearing depending from the top and formed with annular grooves, a plurality of partitions 80 having outer edges resting on the inwardly projecting flange, and bearing rings detachably bolted to said partition and lying in said grooves.

2. A furnace comprising a top section, a 85 tubular bearing depending therefrom, partitions mounted to swing on said tubular bearing, and operating means for the partitions extending through said tubular bearing to the top of the furnace. 90

3. A furnace comprising a top section, a tubular bearing depending therefrom, partitions mounted to swing on the tubular bearing, and individual operating members for the partitions extending through the tubular bearing to the top of the furnace and 95 radially outward in the planes of the partitions.

4. A furnace comprising a top section, a tubular bearing depending therefrom, partitions mounted to swing on the tubular bearing, operating means for the partition extending through said tubular bearing, and means for closing the upper end of the tubular bearing to prevent the passage of hot 100 air therefrom or the entrance of dust there-through. 105

5. A furnace comprising a top section, a tubular bearing depending therefrom, partitions mounted to swing on the tubular bearing, operating means for the partition extending through said tubular bearing, and means for closing the upper end of the tubular bearing to prevent the passage of hot air 110 therefrom or the entrance of dust there-through, said means comprising a cup shaped member, suitable sealing medium for sealing the said cup shaped member about the end of the tubular bearing, and an inverted cup shaped member of smaller size having its 115 margin in the sealing medium. 120

6. A furnace comprising a top section, a tubular member depending therefrom, partitions mounted to swing on said tubular bearing, and operating members detachably connected to said partition and extending through said tubular bearing to the exterior 125 of the furnace.

7. A furnace comprising a top section, a tubular member depending therefrom, parti- 130

tions mounted to swing on said tubular bearing, a cup shaped member surrounding the upper end of the tubular member, a sealing medium in said cup shaped member, an inverted cup shaped member of smaller diameter having its margin embedded in the sealing medium, and operating members for the

partitions extending through the tubular member and outwardly over the top of the furnace, said operating members having deflected portions lying in the sealing medium below the edge of the second mentioned cup shaped member. ¹⁰
